UNITED STATES PATENT OFFICE

HALBERT T. JOHNSON, OF PASO ROBLES, CALIFORNIA

AIR CONDITIONER

Application filed March 18, 1932. Serial No. 599,877.

This invention relates to devices for conditioning air in rooms, by circulating the air and by reason of such circulation purifying the air and also cooling or warming it as well as altering the humidity thereof either to an increased or lessened degree as governed by any particular installation.

The main object of my invention is to provide a self-contained, compact and unitary apparatus of this character which may be either made as a portable unit or a permanent installation, by means of which the air will be thus conditioned in a very efficient manner and at a minimum of operating expense.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a front elevation of the apparatus.

Fig. 2 is a transverse vertical section on the line 2—2 of Fig. 1.

Fig. 3 is a sectional elevation on the line 3—3 of Fig. 2.

Fig. 4 is a fragmentary view showing the means for driving the perforated cone.

Referring now more particularly to the characters of reference on the drawing, the case 1 of the apparatus is preferably flat on the bottom and curved around the top. It is provided in its front face with a circular air discharging opening 2 and at the back with a relatively small intake opening 3 concentric with the opening 2 and surrounded with an inwardly projecting flange 4. An electric motor 5 is disposed in the casing concentric with the openings and is supported from the back of the casing by radial arms 6. Cushion washers W are disposed between the arms and the parts connected thereto so as to absorb vibrations which would otherwise be transmitted from

the motor to the casing. Vibration of the latter is further damped by a suitable lining L extending about the interior of the casing.

The motor is not as large in diameter as the opening 3 so that air can readily flow into said opening all about the motor. Mounted on the motor shaft 7 in front of the motor but inside the casing is a solid disc 8. A fan is secured to this disc which is in the form of a plurality of blades 9 extending from the periphery of the disc over the motor toward the back of the casing. The blades are disposed radially of the axis of rotation and their inner edges are substantially aligned with the inner periphery of the flange 4, as shown in Fig. 2.

Surrounding the fan in clearance relation thereto and extending transversely in the casing from an overlapping relation to the flange 4 to adjacent the front opening 2 is a perforated frusto-conical air conduit 10 which is open on both ends and lined with water absorbing fabric 11. The large end of this conduit is at the front and such end is substantially the same diameter as the opening 2. The conduit is reinforced against collapse by outwardly projecting flanges 12 at its ends. It is supported in concentric relation to the motor and other parts by grooved sheaves 13 mounted in the casing in circumferentially spaced relation and engaging the front flange 12. One of said sheaves has a relatively large drive pulley 14 associated therewith, which is connected in driving relation with the motor shaft in front of the disc 8 by a belt or similar drive 15. The fan and conduit are therefore driven in opposite directions and the latter turns at a slower speed than the fan.

The bottom portion of the casing is water-tight so as to form a tank 16 for the reception of a supply of water into which the lower portion of the conduit dips.

To prevent the lower fan blades from dipping into the water I provide a guard plate 17 immediately above and parallel to the lower portion of the conduit. This plate extends from the front of the casing about the opening 2 to the back flange 4 and has wa-

ter-tight connection therewith; the sides of the plate being at a height equal to that of the bottom of the flange 4 or above the highest possible water level line.

5 A plurality of flexible fabric flaps 18 project outwardly from the conduit so that with the rotation of the latter the flaps successively dip into the water and the lining 11 is kept in a moist condition even though the 10 supply of water in the tank is depleted so that the conduit itself will not dip into the same.

In operation the air to be conditioned is drawn in through the intake opening 3 and 15 by the centrifugal action of the fan blades is thrown against the wet lining of the conduit and thence out through the discharge opening 2 into the room. Any dust etc. in the air as drawn in is thrown against the 20 wet lining and adheres thereto, and will be carried around until it is washed off by the water in the bottom tank. The reverse movement of the fan and conduit relative to each other causes the air passing there- 25 between to be agitated and aids in the separation of the dust and other foreign matter from the air and consequently enhances the purifying action.

Also the air circulating through the 30 device and coming constantly in contact with the wet lining will be humidified. If a disinfectant is added to the water in the tank the air will also be disinfected. As the fabric lining is being continually immersed in 35 the water there is no tendency for any dissolved salts in the water to crystallize on the lining and impair its efficiency. Evaporation of water from the revolving conduit by the rapid passage of air therethrough naturally 40 sets up a cooling effect on the air. This may be increased if desired by placing a cooling coil arrangement 19 in the bottom of the tank and connecting said coil to a refrigerating unit or the like so as to chill the 45 water in the tank to whatever temperature may be desired. If the coil is connected to a heating device the water in the tank will be heated and the air as circulated will be correspondingly warmed.

50 Since the humidifying action varies with the temperature it will be lessened the cooler the water is kept and increased according as the heat of the water is increased. When the device is constructed as a portable unit the 55 tank is re-filled with water as needed but in a permanent installation said tank may of course be connected to a constant source of water supply to automatically maintain the water in the tank at a predetermined level.

60 From the foregoing description it will be readily seen that I have produced such a device as substantially fulfills the objects of the invention as set forth herein.

While this specification sets forth in detail the present and preferred construction

of the device, still in practice such deviations from such detail may be resorted to as do not form a departure from the spirit of the invention, as defined by the appended claims.

Having thus described my invention what I claim as new and useful and desire to secure by Letters Patent is:

1. An air conditioner comprising an open-topped tank for liquid, a horizontal open-ended rotary liquid-absorbing air conduit disposed relative to the tank to dip into the liquid, a fan inside the conduit clear of the liquid, arranged to cause air to be drawn into the conduit from one end and to be then thrown into contact with the inner periphery of the conduit and discharged from the opposite end thereof, and means to rotate the fan and conduit in opposite directions.

2. An air conditioner comprising an open-topped tank for liquid, a motor mounted horizontally over the tank, a fan driven by the motor and comprising a disc secured on the motor shaft and blades extending from the disc over and about the motor, a rotary liquid-absorbing open-ended air conduit about and spaced from the fan blades and arranged relative to the tank to dip into the liquid therein, and means to drive said conduit from the motor.

3. An air conditioner comprising an open-topped tank for liquid, a motor mounted horizontally over the tank, a fan driven by the motor and comprising a disc secured on the motor shaft and blades extending from the disc over and about the motor, a rotary liquid-absorbing open-ended air conduit about and spaced from the fan blades and arranged relative to the tank to dip into the liquid therein, elements turnably supporting said conduit from its periphery, and means to drive one of said elements from the motor.

4. An air conditioner comprising an open-topped tank for liquid, a motor mounted horizontally over the tank, a fan driven by the motor and comprising a disc secured on the motor shaft and blades extending from the disc over and about the motor, a rotary liquid-absorbing open-ended air conduit about and spaced from the fan blades and arranged relative to the tank to dip into the liquid therein, elements turnably supporting said conduit from its periphery, means to rotate the conduit, and a plate disposed between the fan and conduit, said plate extending between and having a water-tight fit with the front and back walls of the tank, and extending circumferentially of the conduit to terminations at a level above the liquid level in the tank.

5. An air conditioner comprising an open-topped tank for liquid, a horizontal air conduit disposed relative to the tank to dip into the liquid, a fan mounted on a horizontal

axis inside the conduit, and means mounted in the tank to prevent direct contact of the fan blades with the liquid even though the level of the liquid is above that of the bottom of the fan.

6. An air conditioner comprising an open-topped tank for liquid, a horizontal air conduit disposed relative to the tank to dip into the liquid, a fan mounted on a horizontal 10 axis inside the conduit, and a plate disposed between the fan and conduit; said plate extending below the fan and between and having a water-tight fit with the front and back walls of the tank with its ends terminating 15 on a level above that of the liquid in the tank.

In testimony whereof I affix my signature.

HALBERT T. JOHNSON.
